CLAIM

The ornamental design for an outdoor wall-mounted area lighting luminaire, as shown and described.

DESCRIPTION

FIG. 1 is a side elevation view of an outdoor wall-mounted area lighting luminaire showing my new design, with the opposite side being a mirror image thereof;

FIG. 2 is a bottom plan view thereof;

FIG. 3 is a top plan view thereof; and,

FIG. 4 is a front elevation view thereof.

The rear surface of the wall mounting structure forms no part of the claimed design and is omitted.
